BELT ABRADER

Phillip J. Robischung, Kalamazoo, Mich., assignor to
Hammond Machinery Builders, Inc., Kalamazoo,
Mich., a corporation of Michigan

Filed Feb. 26, 1962, Ser. No. 68,957

Term of patent 14 years

(Cl. D37—1)

FIGURE 1 is a perspective view of a belt abrader embodying the new design;

FIGURE 2 is a side elevational view thereof;

FIGURE 3 is a top plan view thereof;

FIGURE 4 is an end elevational view of one end thereof; and

FIGURE 5 is an end elevational view of the other end thereof.

I claim:

The ornamental design for a belt abrader, as shown and described.
